(57) **CLAIM**

The ornamental design for a case, as shown and described.

DESCRIPTION

FIG. 1 is a front perspective view of a case, showing my new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is a cross-sectional view thereof, taken along line 9-9 of FIG. 3; and,

FIG. 10 is a cross-sectional view thereof, taken along line 10-10 of FIG. 3.

The broken lines showing a logo in FIGS. 1 and 3 depict environmental matter and form no part of the claimed design. The remaining broken lines represent portions of the case that form no part of the claimed design.
